MULTIPLE-PIVOTED-JAW PIPE WRENCH
WITH INTERCHANGEABLE OBJECT-EM-
BRACING BUSHINGS

James R. Brinkley, Elk Grove, Calif.

Application March 3, 1950, Serial No. 147,340

2 Claims. (Cl. 81—91)

1

The present invention relates to improvements in a multiple-pivoted-jaw pipe wrench with interchangeable object-embracing bushings. It consists of the combinations, constructions, and arrangements of parts, as hereinafter described and claimed.

It is a well-known fact that when ordinary pipe wrenches, such as the Stillson, are applied to pipes, the surfaces of the pipes are marred and roughened to an appreciable extent. The same is true when these wrenches are used for gripping rods, shafts, etc. Moreover, thin-walled pipes often are crushed or distorted when they are turned by conventional pipe wrenches.

Accordingly, an object of this invention is to provide a wrench adapted to grip pipes, rods and the like, without marring the gripped surface, or crushing the object during turning thereof.

More specifically stated, I provide a wrench having coacting jaws provided with smooth bearing surfaces, which are shaped to embrace sections of the object to be gripped. These surfaces are designed to distribute the compressive force of the jaws over a relatively wide area thereby precluding crushing of the object. Inasmuch as the gripping surfaces of the jaws are smooth, no marring of the object will result.

A still further object is to provide a wrench of the character described, which is provided with interchangeable object-embracing bushings. These bushings are designed to bear against objects of various sizes, and serve to spread the compressive force over the gripped area. It is an easy matter to change the bushings so that the jaws will be provided with the proper size bushings to fit an object to be gripped.

Another purpose of this invention is to provide a wrench that may be applied around an object in a rather crowded place, and which will grip the object just as soon as the operating handle of the wrench is moved by the operator. It is well-known that a Stillson wrench, for instance, is so constructed that the handle thereof must be moved through a considerable arc before the jaws are brought into gripping relation with the object. Oftentimes, this arc of "lost motion" takes up all of the room available in which the wrench can be operated.

Other objects and advantages will appear as the specification continues. The novel features of the invention will be set forth in the claims hereunto appended.

Drawings

For a better understanding of my invention,

2

reference should be had to the accompanying drawings, forming part of this application, in which:

Figure 1 is a top plan view of my wrench;

Figure 2 is a side elevation thereof;

Figure 3 is a transverse vertical sectional view taken along the line III—III of Figure 2;

Figure 4 is an end view of the complementary bushings disclosed in Figures 2 and 3;

Figure 5 is an isometric view of one of the bushings;

Figure 6 is an isometric view of my wrench with the several parts thereof opened up and arranged in substantially straight alignment with one another.

Figures 7 and 8 are isometric views of the pair of coacting jaws that I employ; and

Figure 9 is an end view of another set of complementary bushings.

While I have shown only the preferred form of my invention, it should be understood that various changes, or modifications, may be made within the scope of the annexed claims without departing from the spirit thereof.

Detailed description

In carrying my invention into practice, I provide a wrench having a pair of coacting jaws indicated generally at A and B. The jaws are adapted to be moved into confronting relation with one another, as seen in Figure 2, so as to be arranged on opposite sides of an object C to be gripped.

These jaws are fashioned with substantially semi-cylindrical saddles 10 on their confronting faces, which define smooth object-embracing bearing surfaces 11. Openings 12 in the saddles extend from the surfaces 11 to exposed portions of the jaws for the purpose presently to be described.

As clearly shown in Figures 2, 3 and 6, substantially semi-cylindrical bushings D are disposed in the saddles 10 and bear against the surfaces 11 thereof. These bushings have bifurcated pins 14 anchored thereto, with the split ends of the pins projecting through the openings 12 for removably retaining the bushings in their respective saddles. These pins frictionally engage with the walls of the openings 12 through which they are inserted. It is obvious that a screw driver, or the like, may be used for spreading the bifurcated ends of the pins to produce the proper friction. The outer exposed ends of the pins may be tapped with a suitable instrument to aid in the removal of the bushings.

It will be noted that links 15 swingably interconnect rear portions of the jaws. These links allow the jaws to be swung from closed position, as in Figure 2, into fully opened position, as in Figure 6. Other links 16 are hingedly secured by a pin 17 to a forward part of the jaw B. A lever handle E, which may be made of any desired length, is pivoted by a pin 18 of the forward links.

Referring to Figures 2, 6 and 7, I provide a lug 19 on the forward end of the jaw A. The end 20 of the handle E is adapted to overlie the lug 19. When the end 20 of the handle is arranged over the lug 19, as in Figure 2, and the handle is swung in the direction of the arrow 21, the jaws A and B are forced toward one another to grip the interposed object C.

In this connection the bushings D are designed to grip the object C immediately upon swinging the handle E in a direction to force the jaws toward each other. However, upon swinging the handle in the opposite direction, as suggested by the arrow 22, the bushings will release their grip on the interposed object.

When gripping a larger object than the one shown in Figure 2, the bushings D may be omitted. In this event, the semi-cylindrical bearing surface 11 may be utilized for gripping this larger object. On the other hand, the bushings D' (see Figure 9) may be applied to the saddles 10 in order to grip a smaller object C'. Of course, interchangeable bushings of various sizes may be provided. In any case, the compressive force will be applied to the gripped object over a large area, preventing crushing or marring of the object during use of the wrench.

A spring latch F is anchored to the jaw A by any suitable means, for instance countersunk screws 23. The free end of this latch has a hook 24 thereon, which is engageable with a tooth 25 formed on the lever handle E adjacent to the end 20 of the handle. This latch retains the handle end 20 in engagement with the lug 19 during swinging of the handle. However, the hook may be disengaged manually from the tooth at which time the handle E, links 15 and 16, and jaws A and B can be moved into substantially straight alignment with one another, as disclosed in Figure 6.

Summary of operation

In setting up the wrench for gripping an object, such as indicated at C in Figure 1, the set of bushings D is selected that will conform to the exterior surface of this object. The bifurcated ends of the pins 14 are inserted through the openings 12 of the saddles 10, and the outer surfaces of the bushings moved up against the smooth bearing surfaces 11 of the saddles.

The various parts of the wrench may be moved into substantially horizontal alignment with one another, as illustrated in Figure 6. As a matter of fact, the parts may be folded backwards even further. The jaws A and B are applied around opposite sides of the object C to be gripped. Thereafter, the jaws are moved toward one another until the bushings contact with opposing sections of the object C.

Next, the lever handle E is moved until its end 20 overlies the lug 19 and the hook 24 of the spring latch F is engaged over the tooth 25. Upon moving the handle in the direction of the arrow 21, the object C will be gripped, and further movement of the handle in this direction will result in turning the object. When the handle is moved in the direction of the arrows 22, the

grip of the bushings on the object will be released.

The links 15 and 16 will permit the jaws A and B to shift lengthwise of one another until the bushings D center themselves relative to the object to be gripped. The smooth inner surfaces 26 of the bushings will not mar the object; and will distribute the compressive force of the jaws over a larger area, preventing crushing of the gripped object.

The fact that the jaws may be opened into, or beyond, the positions shown in Figure 6, will allow the jaws to be inserted around an object disposed in a rather crowded place. As soon as the handle E of the applied wrench is moved in the direction of the arrow 21, the object will be gripped without appreciable lost motion of the handle.

When disengaging the wrench, the hook 24 is lifted above the tooth 25. At this time the jaws may be moved apart, freeing them from the object. The interchangeable bushings will allow a large range of various sizes of objects to be gripped by my wrench. Obviously, the wrenches may be made in different sizes, depending upon the objects to be gripped and turned. The wrench may be applied to objects, or removed therefrom, with facility and ease.

I claim:

1. In a wrench of the character described: upper and lower coacting jaws movable into confronting relation with one another, and having gripping surfaces arranged to be positioned on opposite sides of an object to be gripped; links swingably interconnecting rear portions of the jaws; a pair of spaced-apart links hingedly secured to a forward part of the lower jaw; a lug disposed on the forward end of the upper jaw, and being insertable between the forward pair of links; a lever handle pivoted to and disposed between the forward links, and having a prying end disposed to overlie and engage with the lug for forcing the jaws toward each other when the handle is swung in a predetermined direction about its pivot; the forward links straddling the lug and handle to preclude lateral slippage of the lug and prying end of the handle relative to one another; the handle having a tooth in the upper surface of its prying end; and a spring latch extending generally lengthwise of the upper jaw and having one end thereof fixed to the upper jaw; the spring latch having a free end provided with a hook engageable over the tooth to prevent the jaws from falling apart during oscillation of the jaws about the object; the spring latch having a set to maintain the prying end of the handle in engagement with the lug during swinging of the handle; the rear and front links being pivoted to the jaws for free shifting of the jaws lengthwise relative to one another for centering the gripping surfaces of the jaws on the object.

2. In a wrench of the character described: a jaw-defining a body portion, and a saddle having parts projecting laterally beyond opposite sides of this body portion; the saddle having a semi-cylindrical bushing-receiving surface on its underneath side; the laterally-projecting parts of the saddle having exposed upper surfaces; the saddle being fashioned with openings extending from the underneath to the upper exposed surfaces thereof; a semi-cylindrical bushing removably abutting the bushing-receiving surface of the saddle; and pins anchored to the bushing and having bifurcated ends frictionally engag-

ing with the walls of the openings to retain the bushing in the saddle; these pins having upper ends exposed and extending above the upper surfaces of the laterally-projecting parts of the saddle; the exposed upper ends of the pins being spaced outwardly from the body portion of the jaw so that they may be tapped with an instrument to aid in the removal of the bushing from the saddle.
